FLIGHT-BAR TYPE ROLLER GIN

Eugene H. Brooks, Sherman, Tex., assignor to Hardwicke-Etter Company, Sherman, Tex., a corporation of Texas

Filed Feb. 10, 1964, Ser. No. 343,724
4 Claims. (Cl. 19—50)

The present invention has reference to ginning cotton, there being provided by this invention new and improved roller gin equipment.

Applicant is aware of the roller gin disclosed in the patent to Williams et al., No. 2,929,111, which is included herein by reference. This patent teaches an improvement in roller gins wherein the ginning roller cooperates with a stationary knife and with chain carried rectangular bars to pull the cotton from the seeds. When the apparatus disclosed in the Williams Patent No. 2,929,111 is utilized for commercial application where the gin has a substantial width, shortcomings in this design become evident. In particular, the chains which support the rectangular flight bars must be very tight. In commercial roller gins, a substantially increased flight-bar length is required together with heavier bars, and it is believed to be commercially impractical to maintain such a chain sufficiently tight to maintain the bars rigid so as to follow rigidly and closely a prescribed pattern of movement essential for prolonged effective ginning. Moreover, the flight bars which carry the seed cotton to the knife in this gin trace a straight-line path relative to the peripheral surface of the gin roller with a consequent reduction in the ginning capacity before the flight bars reach the stationary knife.

The present invention has reference to a roller gin of the character described having a carrier conveyor for the flight wherein a new and improved arrangement for conveying the seed cotton is provided so that a substantially greater amount of actual ginning takes place before the bars reach the leading edge of the stationary knife. To this end, the flight bars trace an arcuate path relative to the peripheral ginning roller surface so that a greater area of contact is provided, and means are provided for varying the orientation of the flight bars so that their bottom surface traces such a path.

Still further according to this invention, there is provided a roller cotton gin with a new and improved arrangement for controlling the angular orientation of the flight bars during ginning operations. The flight bars according to the present invention are carried in a fashion which will positively control their orientation relative to the ginning roller and the stationary knife. A new and improved structure is provided for rigidly and positively mounting the flight bars for movement in their predetermined path.

This invention contemplates a roller cotton gin which is particularly suited for commercial application, wherein the flight bars may be of a substantial length as necessary in commercial ginning operations without sacrificing the precision path of movement of each of the flight bars so necessary for efficient ginning. The flight bars are provided with guide and control rollers attached to their opposite ends which are positively guided in their movement in opposed pairs of guide tracks, arranged on the frame at opposite ends of the ginning roller, and a new and improved structure is provided for linking the flight bars to one another and to ball bearing rollers which move along the tracks. The structure includes means for controlling with a high degree of accuracy the angular orientation of the bars during their movement past the ginning

2

roller and the stationary knife, so as to provide an efficient and reliable ginning apparatus of enhanced capacity.

These and still further objects, advantages and novel features of the invention will become apparent in the specification and claims, taken in connection with the accompanying drawings.

In the drawings:

FIGURE 1 is a diagrammatic side elevational view partially broken out, of the roller gin according to the present invention;

FIGURE 2 is an enlarged sectional elevation view of the roller gin in the region of the apparatus where the ginning takes place;

FIGURE 3 is a view taken along lines 3—3 in FIGURE 2;

FIGURE 4 is a sectional view taken along line 4—4 in FIGURE 3;

FIGURE 5 is a detail elevation view of the flight bar rocking lever which carries and guides the flight bars in the tracks; and

FIGURE 6 is a generally diagrammatic elevational view (partly in section) of an improved modification of the invention.

Referring now to the accompanying drawing, there is shown a roller gin 10 which includes a conventional frame 12 of generally rectangular box-like construction carrying a horizontally extending ginning roller 14, which has a surface covering 16 of known material to which lint fibers adhere. The roller is mounted on a shaft 18 which is adjustably journaled in the opposed side walls of the gin frame 12 and connected to any suitable prime-mover (not shown). An adjustable upwardly inclined stationary knife 20 with a leading edge 21 is mounted on a cross rail 22, in turn, joined at its end to the gin frame 12 by any convenient means (not shown). The knife 20 is upwardly inclined toward the ginning roller 14 in a position so that the seed cotton to be ginned is fed into the roller gin 10 with an inclined seed cotton slide 24 onto the top of the ginning roller 14 at a position upstream or in advance of the leading knife edge 21. By this arrangement, the seed cotton adheres to the surface 16 of the ginning roller 14 and is dragged toward the knife 20.

Fixed on the opposed inner side walls of the frame 12 are identically aligned outside and inside guide tracks 25 and 26 defined by three plates 27, 28, and 29 which extend in a generally rectangular continuous path around the frame as illustrated in FIGURE 1. These guide tracks 25 and 26 are constructed and arranged to carry a continuous set of connected and spaced-apart, generally rectangular, horizontally extending moving flight bars or blades 30a, 30b, 30c, etc., these flight bars being axially oriented parallel to the axis (and peripheral surface) of the ginning roller 14.

In accordance with one important feature of this invention, the flight bars 30 are connected for movement in the general pattern described, by a linkage arrangement which will now be described. The ends of each flight bar 30 carry a connecting flight bar rocking lever 32 which is in the form of a one-piece casting or the like (FIGURE 5) having an end wall 34, a rear wall 36, and a bottom wall 38. The rear wall 36 and bottom wall 38 have apertures 40 receiving machine bolts 42 which rigidly join the levers 32 to each end of the flight bar 30. Each lever 32 has a downwardly, rearwardly, and outwardly inclined arm 44 (as viewed along the upper flight), carrying a horizontally extending boss 46 at its lower end. This boss 46 carries an inside-track ball bearing controlling roller 48 on a threaded pin 50. In this regard, the roller 48 rides in the inside track 26 between the inner

most plate 27 and the intermediate plate 28. The end wall 34 of lever link 32 carries an axially extending boss 52. The exterior surface of this boss 52 carries a smooth plastic bearing sleeve 54 such as of "Teflon" or the like, the sleeve 54, in turn, carrying apertured connecting links 56, 58 so as to pivotally connect each flight bar with the adjacent flight bars. A ball bearing guide roller 60 is carried by the interior of the boss 52 via another threaded pin 62 in a manner identical to that described for the roller bearing 48. The outside guide roller 60, of course, rides in the outside guide track 25 between the intermediate plate 28 and outside plate 29. Connecting links 56 and 58 are retained on the boss 52 by a spacer washer 64. By virtue of this arrangement, it is evident that each lever 32 is integral with the ends of their flight bar 30, and the bottom flat surface 66 of each flight bar 30 can be oriented by varying the path of the guide tracks 25, 26 relative to each other.

Referring to FIGURE 2, another important feature of this invention is shown wherein the guide tracks 25, 26 are operative in conjunction with the connecting lever 32 and its associated rollers 48, 60 to maintain the bottom surface 66 of each flight bar in substantially tangential relationship with the upper side of the ginning roller 14 over a substantial arcuate path in advance of the edge 21 of the knife 20.

As the guide tracks 25 and 26 approach the upper side of the rapidly rotating ginning roller 14, their paths are parallel to the circle of movement of the surface of the ginning roller. Commencing with a transverse cotton inlet opening plate 68 extending across the frame 12 immediately opposite the seed cotton slide 24, the track 25 takes a downward curve to a point slightly past the tip of the knife 20 which curve is concentric with the peripheral surface 16 of the ginning roller 14. This arcuate extent, designated A, constitutes substantially the effective area of ginning with the bottom faces of the flight bars in substantial contact with the surface of the ginning roller during the ginning operation. There is, nevertheless, a slight separation of the flight bar shown at 30d in FIGURE 2, from the surface of the rotating roller gin immediately before reaching the tip of the stationary knife 20.

The inside guide track 26 is parallel with the outside track 25 up to a point past the opening plate 68 and through arc B. It then traces an abruptly oppositely curved path 70 down to a point well beyond the radial extent of the tip of the knife 20. This cooperative path is defined by a curved widened part 72 of the guide plate 28 so that the inside roller 48 makes a quick swing while the roller 60 is entering an outwardly extending part of the track 25, as shown at the flight bar position 30d (FIGURE 2). The positive outwardly guided movement of the flight bar (at 30e), away from the stationary knife 20 allows the seed to pass over the knife to a point of disposal as described in Patent 2,929,111 or seed with attached unginned lint may be pulled back to the tip of the stationary knife 20, to be acted upon by the succeeding flight bar.

By virtue of the linkage connection between the flight bars, the disadvantages of a tightly drawn sprocket chain are avoided and it is not necessary to operate under great tension in order to effect the proper positioning of the flight bars 30, as is the case with the prior art. The flight bars 30 trace their precise path not by tension on sprocket chains but rather by the positive positioning obtained by the guide tracks 25, 26 and the flight bars are brought to and from their ginning positions in a positive manner.

The guide plates 27 and 28 define a track for the rollers 48 which is parallel with the outer track for the rollers 60 throughout the arc B, and then the plates are formed so that the inner track follows an abruptly and oppositely curved path 70 down to a point well beyond the radial extent of the tip of the knife 20, the middle guide plate 28 being widened as at 72 for this purpose.

Any suitable power means may be provided for driving the flight bars 30 through their path shown in FIGURE 1. For example, this drive arrangement may include some type of drive wheel connected to a prime mover (not shown) and positioned in the upper left-hand corner of the gin frame 12 as shown in FIGURE 1, and as illustrated in the Williams et al. Patent, 2,929,111.

During operation, it is evident that cotton introduced into the roller gin 10 via the slide 24 is effectively ginned through the arcuate area A on the top side of the rapidly rotating ginning roller 14 due to the arcuate path traced by the slower moving flight bars 30. Lever means is provided for continuously and positively orienting the bottom flat surface 66 of each flight bar 30 so that the same is flush with the roller 14 during movement through this arcuate path A.

In FIGURE 6 a modification of the invention is shown in which the tracks for the guide rollers and the controlling rollers are reversed, in the sense that the controlling rollers 48' travel in a track 26' outwardly of the track 25' for the guide rollers 60' which carry the flight bars 80.

As in the first described embodiment, there is a ginning or packing roller 14 having a covering surface 16 of molded packing like material, such as rubber and canvas which has affinity for the cotton lint, and the doctor blade or knife 20 is adjustably mounted on a support 22 extending between the end members of the frame of the gin stand, the knife being presented tangentially and with its point in surface contact with the ginning roller and extending in a direction opposite to the counterclockwise direction of rotation of the ginning roller, as shown in FIGURE 6.

As in the embodiment first described, the knife blade may be adjusted by means of mounting screws (not shown) as is known in the art, both as to the amount of tension it exerts on the surface of the ginning roller and as to the angle which it contacts that surface. Again, as in the embodiment first described, the bearings which support the ginning roller may be arranged for both horizontal and vertical adjustments, as is known in the art and not shown, to control the point at which the surface of the ginning roller contacts the knife and to control the clearance between the knife and the lower faces of the flight bars.

The tracks 26' and 25'', as in the first described embodiment, are formed by guide plates 82, 84 and 86 mounted on each side of the frame of the gin stand, at the ends of the flight bars, so that the latter are guided by their ball bearing rollers in their movements from and toward the ginning roller in a controlled manner. The tracks are of such design that the flight bars approach the ginning roller from the right, as shown in FIGURE 6, and the bars are at the proper time rocked or tilted so that their inner ends are substantially tangential to the surface 16 of the ginning roller from a position 80a to about the position 80b just in advance of the edge of the doctor knife 20.

In the immediate vicinity of the edge of the doctor knife, the guiding plates are of such form that the track 25' for the guide rollers 60' takes an outward and abrupt change of direction as at 90, and the track 26' likewise changes abruptly from a circular direction with respect to the surface of the ginning roller, to a direction extending outwardly from the ginning roller, as indicated by the lead lines from the numeral 92.

It will be understood that the adjacent flight bars are pivotally linked to one another, as previously described, and that the controlling rollers 48' and the guide rollers 60' are mounted on opposite ends of levers 32'.

As in the embodiment previously described, the design is such that at the point or edge of the doctor knife 20, the inner faces of the flight bars 80 clear the stationary knife by approximately thirty thousandths (.030) of an inch. At a point approximately $\frac{5}{8}$ " beyond the edge 75 of the knife 20, the inner faces of the flight bars are

spaced from the stationary knife approximately one hundred and seventy-five thousandths (.175) of an inch, this being a distance sufficient to allow cotton seed which still has lint attached to it, to be pulled back (or to the right as viewed in FIGURE 6) to the point or edge of the knife 20, whereby further ginning action as described in the prior art Williams et al. Patent No. 2,929,111 is accomplished, but with greater efficiency, as previously referred to.

That is, from approximately the position of a flight bar as indicated at 80a, over to the position where the flight bars start to pass over the edge of the doctor knife 20, there is ginning action performed by the cooperation of the ginning roller and the flight bars, the surface of the ginning roller being moved at a much greater speed than the speed of movement of the flight bars, whereby lint which is engaged by the surface of the ginning roller is carried under the inner faces of the flight bars, with the seed being restrained by the flight bars, so that some of the lint is removed from the seeds. As previously mentioned, this ginning action is carried out over a much greater area of the ginning roller, or throughout a greater arc of movement, than is possible in prior art constructions. When the flight bar reaches the position 80b, where it passes over the edge of the knife 20, the action of the guide rollers 60' and the controlling rollers 48', operating in their tracks, and connected as they are by the levers 32', is such as to positively and abruptly move the flight bars outwardly away from the outer surface of the doctor blade 20, while successively tilting the flight bars as indicated between position 80b and 80c, thus enabling the seed to pass over the doctor blade, and to be discharged to a suitable conveyor, or to be pulled back toward the point of the knife if any lint remains upon the seed and is still engaged by the surface of the ginning roller. Of course, as previously described, in connection with the first mentioned embodiment, and as referred to in the Williams et al. Patent No. 2,929,111, such seed as is pulled back to the edge of the doctor blade, will be subsequently engaged by a succeeding flight bar, and it will be carried away and stripped from its lint, which adheres to the surface of the ginning roller.

In order to press the locks of cotton down on to the ginning roller, to improve the ginning action, an auxiliary pressure roller 96 is provided, being mounted for turning movement on a shaft 98 which is carried between arms 100 at opposite ends of the frame, and which in turn are pivoted to the frame of the gin stand as at 102. A weighted handle 103 may be provided to lift the pressure roller, which tends to move downwardly by its own weight and which is thus yieldingly mounted and thus may be lifted around its own pivot by the pressure of any excessive amount of cotton. The pressure roller 96 is provided with radially extending segments 104 which are of such size and are so positioned that they will mesh in the spaces between the flight bars, and when the pressure roller is turned by the movement of the flight bars, these segments press the locks of cotton down toward and against the surface of the ginning roller in order to facilitate the ginning action as previously described.

As in the principal embodiment, there is a lint slide provided at 106, to deliver the cotton into the ginning area, at about the flight bar position 80a.

The outer ends of the pressure roller segments 104 are arranged to clear the packing roller by approximately $\frac{3}{8}$ ".

It will be understood that the embodiment of FIGURE 6 is illustrated in a more or less diagrammatic manner, and that conventional supporting and driving means for the parts may be provided as is well known in the art.

From the foregoing description of the various embodi-

ments of this invention, it is evident that the objects of this invention, together with many practical advantages are successfully achieved. While preferred embodiments of my invention have been described, numerous further modifications may be made without departing from the scope of this invention.

Therefore, it is to be understood that all matters herein set forth or shown in the accompanying drawings are to be interpreted in an illustrative, and not in a limiting sense.

What is claimed is:

1. In a roller cotton gin having a frame, a cylinder mounted in said frame having a surface suitable for roller ginning, means for rotating said surface at a relatively high speed, a doctor knife adjustably carried by said frame and having a top substantially flat surface terminating in an edge presented tangentially against the direction of rotation of said surface and substantially in contact therewith, means for delivering seed cotton to said surface in advance of said knife, a plurality of ginning blades for cooperation with the surface of said ginning roller and with said knife, a carrier conveyor having means for mounting said blades in spaced apart relationship thereon and for guiding them in their movement so that their inner faces almost contact said surface and travel toward and with the direction of movement of said surface in the area immediately in advance of said knife, but at a speed substantially less than the surface speed of said cylinder, means for moving the ginning blades as specified, said carrier conveyor having positively acting means for positioning and abruptly swinging the edges of said blades outwardly over the edge of said knife and away from the upper surface of said knife, whereby the seeds are ginned from the cotton to a substantial extent in the area in advance of the edge of said knife, and again by being pulled by lint adhering to said surface back over the upper surface of said knife to its edge where they are then contacted and finally ginned over the edge of said knife by a succeeding blade on said carrier conveyor, and a pressing roller rotatably mounted in said frame for turning movement about an axis parallel to the axis of said cylinder, said pressing roller having radially extending segments which pass into the spaces between said ginning blades upon rotation of said pressing roller and which press the seed cotton against the surface of said ginning cylinder in advance of said doctor knife.
2. A roller gin as in claim 1 wherein said pressing roller is freely rotatable and is rotated during operation of said gin by engagement of said radially extending segments with the moving ginning blades.

3. A roller gin comprising: a horizontally extending ginning roller having a surface to which fibers adhere; means for rotating said ginning roller; cotton feeding means adjacent the upper side of said roller; a knife positioned across the surface of said roller in a position downstream of said feeding means in the direction of rotation of said roller; a plurality of spaced apart flight bars each having a bottom surface; means for moving said flight bars in a predetermined path; guide means for positively guiding said flight bars through an arcuate portion of said path coincident with the periphery of said roller immediately before said knife, said guide means including means pivotally connecting each flight bar to the next adjacent flight bar, a lever connected to each end of each flight bar and extending therefrom in a vertical plane, a first guide element carried at the end of each lever and a second guide element carried on each lever in vertically offset relationship to said first guide element, first and second guide tracks having curved portions positioned on each side of said ginning roller and operatively engaging said first and second guide elements, respectively, whereby the offset relationship of said guide elements and tracks effects rapid swinging movement of said flight bars by lever action operating through said

levers in accordance with the curvatures of said tracks; and a pressing roller rotatably mounted for turning movement about an axis parallel to the axis of said ginning roller, said pressing roller having radially extending segments which pass into the spaces between said flight bars upon rotation of said pressing roller and which press the seed cotton against the surface of said ginning roller in advance of said knife.

4. A roller gin as in claim 3 wherein each of said second guide elements is in general alignment with the axis of its respective flight bar and wherein said first and second tracks are parallel to each other and to the circle of movement of the surface of said ginning roller as they approach the latter and wherein the curvature of said first track then changes so as to effect a quick swinging movement of each lever so as to move the respective flight bar away from said ginning roller at the location of said knife.
